[57] **CLAIM**

The ornamental design for a “race car,” as shown and described.

DESCRIPTION

FIG. 1 is a three-quarter front perspective view of a “race car,” showing my new design;

FIG. 2 is a left side elevational view thereof, the right side being a mirror image;

FIG. 3 is a top plan view thereof;

FIG. 4 is a front elevational view thereof; and,

FIG. 5 is a rear elevational view thereof.

The bottom of the race car forms no part of the claimed design.
